UNITED STATES PATENT OFFICE.

CORNELIS F. M. VAN BERKEL, OF ROTTERDAM, NETHERLANDS, ASSIGNOR TO U. S. SLICING MACHINE COMPANY, OF LA PORTE, INDIANA, A CORPORATION OF INDIANA.

SLICE STACKER.

Application filed August 16, 1926, Serial No. 129,412, and in Germany June 9, 1925.

This invention relates to mechanism for slicing meat or other commodities and for stacking the slices on a receiving tray or table. The object of the invention is to provide improved conveyor mechanism for the slices.

The invention is exemplified in the combination and arrangement of parts shown in the accompanying drawing and described in the following specification, and it is more particularly pointed out in the appended claims.

In the drawing:—

Fig. 1 is an elevation of a slicing machine having one embodiment of the present invention applied thereto;

Fig. 2 is a section on line 2—2 of Fig. 1.

The numeral 10 designates the base of a slicing machine having a rotary slicing knife 11, a reciprocating table 12 for presenting the material to the knife to be sliced, and an operating hand-wheel 13. The table 12 travels on guideways 14 and 15. A supporting plate or bracket 16 is secured to the front edge of the base 10 and carries the conveying mechanism by means of which the slices are transferred from the material as they are sliced and brought to a position where they may be discharged on to the receiving tray or support. Stacking mechanism of this nature is more fully described in my prior Patents #1,290,425, granted January 7, 1919, and #1,573,953, granted May 15, 1924.

Carried by the plate 16 and spaced upwardly therefrom by spacing bolts 17 and bearing sleeves 18 is a guide plate 19 having a peripheral flange 20 thereon. Spaced inwardly from the flange 20 is a second flange 21 held in place by angle brackets 22. The flanges 20 and 21 provide a guide slot for receiving a metal band or tape 23, preferably made of steel. The band 23 projects upwardly above the top edge of the flanges 20 and 21, as shown in Fig. 1. Spaced upwardly from the plate 19 and supported thereon by spacing bolts 24 is a second guide plate 25 having a peripheral flange 26 and an inner flange 27 held in place by brackets 28 in a manner similar to the flanges on the lower guide plate 19. A band 29 similar to the band 23 is guided between the flanges 26 and 27 and projects downwardly below the lower edges of the flanges. The

two metal bands 23 and 29 are connected by a series of spaced, upright bars 30 which are riveted or otherwise attached to the inner faces of the projecting portions of the bands. The parts 30 are provided with pointed pins 31 and are shaped as shown in Fig. 1 to bring the ends of the pins in substantial alinement with the metal bands 23 and 29. The metal bands are driven by discs 32 secured to a shaft 33, the lower end of which is journalled in the bearing 18 on the plate 16 and the upper end of which is journalled in a bearing 34 on the plate 25. The discs 32 are provided with notches 35 for receiving the bent ends of the bars 30 which form spaced projections on the bands 23 and 29 by means of which the bands are positively driven when the shaft 33 is rotated. The lower end of the shaft 33 is provided with a gear 36 which meshes with a pinion 37 carried on a stud shaft 38. The upper end of the shaft 38 is provided with a pinion 39 which meshes with a rack 40 carried by the reciprocating table 12. In this way, the movement of the table 12 drives the bands 23 and 29 and, consequently, the toothed bars 30, to cause the teeth on the bars to engage the slice and carry it away from the slicing knife as it is formed. It is not necessary that the bands 23 and 29 be continuous, but, instead they may be made of strips having their ends disposed adjacent each other but separated, as shown at 41 in the drawing.

The flanges 20 and 26 may be provided with removable sections 42 at one end thereof which are releasably held in place to close the ends of the guide slots for the steel bands. By removing the sections 42, the bands may be withdrawn from their guides, together with their attached toothed bars, for cleaning or repairs.

The steel bands for supporting the conveyor bars have many advantages over the chain construction shown in my prior patents referred to above. The chains require many parts and are, therefore, expensive to manufacture, and, furthermore, it is difficult to make chains of this nature so that they will operate noiselessly. Because of the many pivotally connected portions of the chain which are subjected to alternate tension and compression, the chains are subject to wear and require considerable power for their operation. These disadvantages

are avoided by the use of the steel bands comprising the present invention.

I claim:

1. A slice conveyer comprising a metal tape, means attached to said tape for transporting slices, a pulley having peripherally spaced notches therein for driving said tape, and projections secured to the faces of said tape for engaging said notches.
- 10 2. A slice conveyer comprising a thin metal tape, a guide having a groove in which said tape is slidably mounted, one edge of said tape being arranged to project from said groove, and slice engaging members attached to the projecting portion of said tape.
- 15 3. A slice conveyer comprising a thin metal tape, a guide having a groove in which said tape is slidably mounted, one edge of said tape being arranged to project from said groove, slice supporting means connected with said tape, and a driving pulley arranged to engage the projecting portion of said tape.
- 20 4. A slice conveyer comprising a metal tape having disconnected ends, slice engaging means secured to said tape, a guide having an endless groove therein for receiving

said tape, and a driving pulley for operating said tape in said groove.

5. A slice conveyer comprising a metal tape having separated ends, a guide having an endless groove therein for receiving said tape, a drive pulley for moving said tape in said groove, and slice engaging means carried by said tape, said guide having a removable section to permit said tape to be withdrawn from said groove.

6. A slice conveyer comprising a pair of spaced guides having registering endless grooves therein, metal tapes disposed in said grooves and having the edges thereof projecting therefrom, bars connecting the projecting edges of said tapes, slice engaging pins on said bars, pulleys engaging the projecting edges of said tapes for driving said tapes, and means for rotating said pulleys, said spaced guides having removable sections to permit said tapes to be withdrawn from said grooves.

In testimony whereof I have signed my name to this specification on this 27th day of July A. D. 1926.

CORNELIS F. M. VAN BERKEL.
